UNITED STATES PATENT OFFICE.

MINNA BOBENE KRAFTHEFER, OF CHICAGO, ILLINOIS.

DESIGN FOR A CLOTHES HANGER.

Application filed October 24, 1927. Serial No. 23,867. Term of patent 14 years.

To all whom it may concern:

Be it known that I, MINNA BOBENE KRAFTHEFER, a citizen of the United States, residing at Chicago, in the county of Cook and State of Illinois, have invented a new, original, and ornamental Design for Clothes Hangers, of which the following is a specification, reference being had to the accompanying drawing, forming part thereof.

I claim:

The ornamental design for a clothes hanger, as shown.

MINNA BOBENE KRAFTHEFER.
